UNITED STATES PATENT OFFICE

2,104,865

PILOT AND PILOT COUPLER

George T. Johnson and Harry H. Wolfe, Columbus, Ohio, assignors to The Buckeye Steel Castings Company, Columbus, Ohio

Application November 6, 1935, Serial No. 48,573

18 Claims. (Cl. 213—4)

This invention relates to improvements in train couplers and more especially to a novel locomotive pilot coupler, coupler pocket and coupler-operating mechanism.

5 Most locomotives used in train service do not require constant use of the pilot coupler, and the pilot coupler is not used at all by the locomotive when it is at the front end of freight or passenger trains. It is desirable, from the standpoint of 10 safety, not to have a pilot coupler projecting beyond the contour of the locomotive pilot when the locomotive is at the front end of the train, due to the coupler catching highway vehicles at grade crossings and rolling the vehicles in front of or 15 under the front end of the locomotive, thereby causing derailment of locomotive and greater damage to occupants of both highway vehicles and trains than if the pilot is free of projections, giving the vehicles more chance to be thrown to 20 one side or the other of the locomotive.

The following are the main objects of the invention:

1. A pilot coupler that may be readily swung to a position within the contour of the pilot when 25 not used in coupling.
 2. A pilot and coupler arranged so that when the coupler is moved from its coupling position it is retained in a position which frees the pilot from any projecting surfaces.
 3. A coupler having its surface contour arranged so that when it is moved from its coupling position the coupler presents a surface conforming substantially to the contour of the pilot.
 4. A pilot, coupler, and coupler-operating mechanism arranged so that when the coupler is moved from its coupling position the coupler-operating mechanism also moves into a position that eliminates any projections in front of the pilot and is retained in its out-of-the-way position.
 5. A pilot having a substantially unbroken contour and a coupler arranged in a pocket of the pilot in a manner so that when it is desired to couple at the pilot end of a locomotive the coupler head projects for coupling.

45 The invention is just as applicable to the rear end of "stream-lined" trains or to the front and rear of rail motor car units or other equipment on which it is desirable to "stream-line" or shroud the ends. Therefore, a further object of the invention is to supply improved couplers, coupler pockets and coupler-operating devices especially suitable for such purposes.

With the foregoing objects outlined and with other objects in view which will appear as the 55 description proceeds, the invention consists in the

novel features hereinafter described in detail, illustrated in the accompanying drawings and more particularly pointed out in the appended claims.

In the drawings:

Fig. 1 is a front elevation of a locomotive pilot provided with one form of our improved coupling mechanism.

Fig. 2 is a top plan view of the same with the coupler in retracted position.

Fig. 3 is a similar view with the coupler in projected position.

Fig. 4 is another top plan view with the coupler-operating mechanism removed.

Fig. 5 is a vertical sectional view taken on the 15 line 5—5 of Fig. 2.

Fig. 6 is a detail of the coupler link operating mechanism taken on the line 6—6 of Fig. 3.

Fig. 7 is a perspective view of the operating mechanism shown detached from the pilot.

Fig. 8 is a vertical sectional view of a modification and showing the coupler in retracted position.

Fig. 9 is a similar view with the coupler in projected position.

Fig. 10 is a plan view of the carrier iron of the mechanism shown in Figs. 8 and 9.

Fig. 11 is a side elevation of said iron.

Fig. 12 is a top plan view of the modification.

Fig. 13 is a front elevation of the same.

Referring to the form of the invention shown in Figs. 1 to 7 inclusive, 19 designates a locomotive pilot having a pocket 20 which may be cast integral with the pilot or may be a separate casting secured to the pilot in any suitable way. In 35 other words, the pocket casting may be a separate unit adapted to be secured to the other parts; it may be integral with the pilot beam at the upper end of the pilot; the pocket casting, pilot beam and pilot may be integral; the pocket casting and center portion of the pilot may be integral or any other suitable combination of the front end castings may be employed within the spirit of our invention.

In connection with the foregoing it may be 45 explained that the pilot is considered to be the sloping portion below the pilot beam and in these cases the pilot beam has the same slope as the pilot.

At the rear end of a "stream-lined" train or 50 car, neither a pilot nor a pilot beam is used, although a sloping shroud may or may not be employed. In accordance with our invention the pocket casting may be separate from or integral with the shroud or rear end of such a train or car.

A coupler 21 of special form is pivotally mounted in the pocket on a vertical pin 22 so as to allow the coupler to be moved in a horizontal plane. This allows the coupler to be moved from retracted to coupling position, and when the coupler is housed in the pocket its front face conforms with the face of the pilot to substantially eliminate any projecting parts.

For the purpose of holding the coupler in housed position, the tail of the coupler is provided with a notch 23 to engage a retaining pin 24 that may be inserted in holes 25 and 26 in the top and bottom respectively of the pocket. The same pin or key limits the swinging movement of the coupler in one direction when the coupler is in coupling position, for in such position the notch 27 in the pilot-contoured side of the coupler can engage the pin. Of course, the pin is removed when it is necessary to swing the coupler from retracted to coupling position or vice versa.

The roof of the coupler pocket is provided with an arc-shaped notch 27 to accommodate the lock-lifting mechanism of the coupler and when the coupler is in housed position, a horn 28 on the coupler projects into and closes said slot.

The lock-lifting mechanism consists of a horizontal rock shaft 29 pivoted in bearings 30 on the top of the pilot and having handles 31 at its ends to allow the mechanism to be operated from either end of the pilot. An arm 32 projects forwardly from the rock shaft and terminates in a horizontal loop 33. A link 34 has an eye 35 at one end engaging one side of the loop 33 and from this side of the loop 33 the link 34 extends over and rests on the opposite side of the loop. The link is offset at 48 to provide a substantially vertical shoulder which abuts the inner surface of the last mentioned side of the loop and causes the link 34 to move concentric with the pin 22, thus preventing the eye from binding on the rear of loop 33. An eye 36 at the opposite end of the link engages any suitable connecting means, such as a hook 37 projecting from the locking mechanism of the coupler. The flexible joints provided by such mechanism allow the coupler to be moved from housed position to coupling position without interference by the operating mechanism of the coupler lock. For the purpose of holding the link 34 in the desired positions, a hump 38 is arranged on the loop 33. When the link 34 is rearwardly of the hump, the latter will prevent the link from moving forwardly while the coupler is in housed position. On the other hand when the coupler is projected, the link will ride over the hump and then the front end of the hump will prevent the link from moving rearwardly.

From Fig. 2, it may be seen that when the coupler is in closed position any force acting against the contoured plate on the coupler will be restrained at three places, namely: pin 24, pin 22, and through the guard arm of the coupler abutting the rear wall of the pocket.

It is customary to provide locomotive pilot couplers with means for adjusting coupler height, and for the purposes of the present invention, shims 39 may be arranged on the pivot pin 22 between the top of the coupler and the roof of the pocket. Other shims 40 may be used if desired. These will surround the upwardly projecting boss 41 on the floor of the pocket and form a bearing for the lower edge of the coupler.

In coupler applications it is important to provide freedom for horizontal angling of the coupler in coupled positions. It is furthermore im-

portant to limit the angling of the coupler by means of substantial limiting stops. We mentioned previously the substantial limiting stop afforded by key 24 when the coupler, in coupling position, is angling toward the guard arm side. 5

The substantial limiting stop, when the coupler is angling toward the knuckle side in coupling position, is that on the pilot defined by the substantially triangular surface 42 of the pilot contacting a corresponding surface on the pilot-contoured surface of the coupler. This stop has been developed from the standpoint of providing suitable bearing area without exposing excessive opening in the pilot contour when the coupler is in non-coupling position. The opening which in 15 this construction is exposed, is of the form of a triangular based pyramid as shown at 43 in Fig. 1.

From that figure our arrangement of related surfaces fulfilling the following important requirements may be seen:

(1) Substantially complete closure of the pilot contour along the line 44.

(2) Clearance as afforded by space between the knuckle side of the coupler and the edge 45 25 of the contoured plate to allow:

a. Knuckle to swing open for coupling.

b. Clearance for guard arm of engaging coupler.

(3) Substantial bearing area 46 at butt end of 30 shank is effected by proper consideration having been given to requirement (2) and the requirement of providing sufficient horizontal angling of coupler (in coupler position), toward knuckle side, and the requirement of avoiding excessive 35 opening at the edge 43 when the coupler is in non-coupling position.

It should be understood that the rear end of the coupler when in coupled position abuts the rear wall of the pocket as shown at 46 in Fig. 3. 40

In the modification shown in Figs. 8 to 13 inclusive, the coupler swings downwardly into housed position instead of side ways. Referring to the last-mentioned figures, 50 designates a horizontal pivot pin on which a sleeve 51 rocks. 45 This sleeve has a projecting arm 52 on which is pivoted the rear end of the coupler 53 by means of a pivot pin 54. The coupler in this instance is provided with a pilot-contoured plate 55 and this has a hole 56 to accommodate the lock-lifting 50 mechanism of the coupler which may be of the same construction shown in Fig. 7 with the exception that the hook 37 will have to be connected to the eye 57 of the lock-lifting portion of the coupler by means of a suitable detachable 55 fastening.

When the coupler is in housed position an abutment 58 on the coupler will engage a stationary abutment 59 of the pocket casting 60, and a removable pin 61 may be passed through a 60 sleeve 62 in the roof of the pocket and engage the coupler for holding it in non-coupling position. When the pin is removed the coupler may be swung into coupling position, illustrated in Fig. 9, and then the carrying iron 63 may be 65 swung upwardly to form a bearing support for the coupler. The carrier iron is pivotally mounted as shown at 64 on one side of the pocket and when the iron is swung from vertical to horizontal position it can be held in the latter 70 position by passing a retaining key 65 through apertures 66 and 67 provided respectively in the pocket and carrier iron.

In order to allow horizontal swinging movement of the coupler when in coupling position,

a clearance space 68 is provided between the sleeve 51 and the coupler, and the pocket casting has notches 69 to accommodate the edges of the pilot-contoured face 55 of the coupling.

5 In the foregoing description we have explained our invention in connection with a pilot, but as heretofore mentioned, the invention is not to be confined to such use as it can also be employed at the rear end of "stream-lined" trains 10 or at the front and rear of rail motor car units or in the equipment on which it is desirable to "stream-line" or shroud the ends. It will therefore be understood that in the following claims where we refer to "a locomotive pilot having a 15 pocket", we intend this expression to also include a pocket arranged in the rear end of "stream-lined" trains or in the front or rear of rail motor car units or other equipment on which it is desirable to "stream-line" or shroud the 20 ends. Obviously in such constructions the contoured plate of the coupler will conform to the shape of the shroud or end of the car or the like.

While we have disclosed what we now consider to be preferred embodiments of the invention, 25 we are aware that changes may be made in the details disclosed without departing from the spirit of the invention as expressed in the claims.

What is claimed and desired to be secured by Letters Patent is:

30 1. In improvements of the character described, a locomotive pilot having a pocket, a coupler adapted to be housed in the pocket and movably mounted to permit the same to be moved from a position within the pocket to coupling position 35 and vice versa, said coupler having a pilot-contoured plate substantially conforming with the contour of the pilot when the coupler is in housed position, said coupler having a lock-lifting element and the pocket having a slot to accommodate 40 date said element when the coupler is moved into housed position.

2. In improvements of the character described, a locomotive pilot having a pocket, a coupler adapted to be housed in the pocket and movably 45 mounted to permit the same to be moved from a position within the pocket to coupling position and vice versa, said coupler having a pilot-contoured plate substantially conforming with the contour of the pilot when the coupler is in housed 50 position, said coupler having a lock-lifting element and the pocket being provided with a slot to accommodate said element, and means for closing said slot.

3. In improvements of the character described, 55 a locomotive pilot having a pocket, a coupler adapted to be housed in the pocket and movably mounted to permit the same to be moved from a position within the pocket to coupling position and vice versa, said coupler having a pilot-contoured plate substantially conforming with the contour of the pilot when the coupler is in housed 60 position, said coupler having a lock-lifting element and the pocket being provided with a slot to accommodate said element, and means for closing said slot, the last-mentioned means comprising a horn projecting from the coupler.

4. In improvements of the character described, 65 a locomotive pilot having a pocket, a coupler adapted to be housed in the pocket and movably mounted to permit the same to be moved from a position within the pocket to coupling position and vice versa, said coupler having a pilot-contoured plate substantially conforming with the contour of the pilot when the coupler is in housed 70 position, said coupler having a lock-lifting ele-

ment, a link connecting the lock-lifting element and having an eye at one end thereof, a rock shaft, an arm projecting from the rock shaft and having a loop, said link resting on said loop and the eye of the link surrounding a portion of 5 the loop.

5. In improvements of the character described, a locomotive pilot having a pocket, a coupler adapted to be housed in the pocket and movably mounted to permit the same to be moved from a 10 position within the pocket to coupling position and vice versa, said coupler having a pilot-contoured plate substantially conforming with the contour of the pilot when the coupler is in housed position, said coupler having a lock-lifting element, 15 a link connecting the lock-lifting element and having an eye at one end thereof, a rock shaft, an arm projecting from the rock shaft and having a loop, said link resting on said loop and the eye of the link surrounding a portion of the 20 loop, and means for holding the link in different positions.

6. In improvements of the character described, a locomotive pilot having a pocket, a coupler adapted to be housed in the pocket and movably 25 mounted to permit the same to be moved from a position within the pocket to coupling position and vice versa, said coupler having a pilot-contoured plate substantially conforming with the contour of the pilot when the coupler is in housed 30 position, said coupler having a lock-lifting element, a link connecting the lock-lifting element and having an eye at one end thereof, a rock 35 shaft, an arm projecting from the rock shaft and having a loop, said link resting on said loop and the eye of the link surrounding a portion of the loop, and a hump mounted on one of said members for holding the link in different positions.

7. In combination, a pilot having a pocket, a 40 vertical pivot pin in the pocket, a coupler pivotally mounted on said pin, shims cooperating with the pivot pin and coupler for adjusting the coupler height, said coupler having a pilot-contoured face which substantially closes the mouth of the pocket 45 when the coupler is in housed position, said coupler having a lock-lifting element and said pocket being slotted to accommodate said element.

8. In a pilot coupler having a vertical pivot pin, a rock shaft, an arm rigid with the rock shaft 50 and terminating in a loop, said loop being concentric with the axis of the pivot pin, a link resting on said loop and having an eye at one end engaging said loop, the opposite end of the link being provided with means for connecting the same 55 to a lock-lifting element of a coupler.

9. In a pilot coupler having a vertical pivot pin, a rock shaft, an arm rigid with the rock shaft and terminating in a loop, said loop being concentric with the axis of the pivot pin, a link 60 resting on said loop and having an eye at one end engaging said loop, the opposite end of the link being provided with means for connecting the same to a lock-lifting element of a coupler, one of said parts being provided with a hump for holding the link in different positions relatively to said loop.

10. In mechanism of the character described, a coupler having a vertical pivot pin, a horizontal rock shaft, an arm fixed to the rock shaft, projecting forwardly therefrom and terminating in a horizontal loop, said loop being concentric with the axis of said pivot pin, a substantially horizontal link having its medial portion resting on one side of said loop, the rear end of the link 75

having an eye engaging the opposite side of the loop, and means at the front end of the link for engaging a lock-lifting element of said coupler.

11. In mechanism of the character described a horizontal rock shaft, an arm fixed to the rock shaft, projecting forwardly therefrom and terminating in a horizontal loop, a substantially horizontal link having its medial portion resting on one side of said loop, the rear end of the link having an eye engaging the opposite side of the loop, and means at the front end of the link for engaging a lock-lifting element of a coupler, said loop having a hump projecting upwardly and cooperating with the link for limiting sliding movement of the link on the upper surface of the loop.

12. In mechanism of the character described, a locomotive pilot having a pocket, a vertical pivot pin in the pocket, a coupler mounted for turning movement on said pin and having a pilot-contoured face, said coupler having a lock-lifting element, and means for lifting the last-mentioned element, said means having a swivel joint in line with the axis of the pin to allow a portion of said means to move with the lock-lifting element of the coupler when the latter is swung from a housed position with the pocket to coupling position and vice versa.

13. In mechanism of the character described, a locomotive pilot having a pocket, a horizontal pivot pin in the pocket, a member mounted for rocking movement about the axis of said pivot pin, a second pivot pin carried by said member and having its axis arranged at an angle to the axis of the first-mentioned pivot pin, a coupler swiveled on the second pivot pin and having a pilot-contoured plate to close the mouth of the pocket, and a movable carrier iron for supporting the coupler when the latter is in coupling position.

14. In improvements of the character described, a locomotive pilot having a pocket, a coupler adapted to be housed in the pocket and movably mounted to permit the same to be moved from a position within the pocket to coupling position and vice versa, said coupler having a pilot-contoured plate substantially conforming with the contour of the pilot when the coupler is in housed position, said plate being notched, and a retaining pin cooperating with the notch for limiting the movement of the coupler in one direction when the coupler is in coupling position.

15. In improvements of the character described, a locomotive pilot having a pocket, a coupler adapted to be housed in the pocket and movably mounted to permit the same to be moved from a position within the pocket to coupling position and vice versa, said coupler having a pilot-contoured plate substantially conforming with the

contour of the pilot when the coupler is in housed position, said plate being notched and said coupler also being notched, and a retaining pin cooperating with said notches for holding the coupler in housed position or for limiting movement of the coupler when it is in coupling position.

16. In improvements of the character described, a locomotive pilot having a pocket, a coupler pivoted for movement about a vertical axis and movable from a position within the pocket to coupling position and vice versa, said coupler having a lock-lifting element, a link connected to the lock-lifting element and having an eye at one end thereof, an arm projecting from the rock shaft and having a loop, said loop being concentric with said axis, said link resting on one side of said loop and the eye of the link surrounding the opposite side of the loop, the link having an offset portion forming a shoulder engageable with the inner surface of the loop at the first mentioned side of the latter.

17. In mechanism of the character described, a locomotive pilot having a pocket, a coupler adapted to be housed in the pocket and movably mounted to permit the same to be moved from a position within the pocket to coupling position and vice versa, said coupler having a pilot-contoured face for substantially closing the mouth of the pocket when the coupler is housed within the pocket, a pivot pin connecting the coupler to the pocket, and a removable key for retaining the coupler in housed position, the head end of the coupler when in housed position being adapted to bear against a portion of the pocket whereby when the coupler is in housed position any force acting against the coupler will be restrained by the pivot pin, the retaining key and the abutting surfaces of the head of the coupler and said portion of the pocket.

18. In improvements of the character described, a locomotive pilot having a pocket, a coupler adapted to be housed in the pocket and movably mounted to permit the same to be moved from a position within the pocket to coupling position and vice versa, said coupler having a lock-lifting element, a link connected to the lock-lifting element and having an eye at one end thereof, a rock shaft, an arm projecting from the rock shaft and having a loop, said link resting on one side of said loop and the eye of the link surrounding the opposite side of the link, a portion of the link being offset to provide a shoulder slidably engaging the inner surface of the loop, and a hump mounted on one of said means for holding the link in different positions.

GEORGE T. JOHNSON.
HARRY H. WOLFE.
